(57) **CLAIM**

The ornamental design for pulley for surgical instrument, as shown and described.

DESCRIPTION

1. Pulley for surgical instrument

1.1 : Perspective

1.2 : Front

1.3 : Back

1.4 : Left

1.5 : Right

1.6 : Top

1.7 : Bottom

The ornamental design for a pulley for surgical instrument, as shown and described; the dashed broken lines in the

(Continued)

drawings show portions of the pulley for surgical instrument that form no part of the claimed design.
